ROCKET SHIP

Alex A. Rommel, Fresno, Calif.

Application January 18, 1957, Serial No. 44,525

Term of patent 14 years

(Cl. D71—1)

Fig. 1.

Fig. 2.

Fig. 3.

Fig. 1 is a top plan view of a rocket ship showing my new design.

Fig. 2 is a side elevation thereof. The opposite side of the rocket ship from that shown is the same in appearance as the side shown.

Fig. 3 is a front end elevation of the rocket ship.

I claim:

The ornamental design for a rocket ship, as shown.
